SHORT-WAVE THERAPY APPARATUS

James N. Shirley, Overland Park, Fred M. Berry, Leawood, and Eugene C. Lipsky, Prairie Village, Kans., assignors to International Medical Electronics Ltd.

Filed Feb. 1, 1971, Ser. No. 111,792

Term of patent 14 years

Int. Cl. D24—02

U.S. Cl. D83—1

Fig. 1.

Fig. 2.

Fig. 3.

*Fig. 4.**Fig. 5.**Fig. 7.**Fig. 6.*

FIG. 1 is a perspective view of the short-wave therapy apparatus embodying our new design;

FIG. 2 is a top plan view of a short-wave therapy apparatus embodying the new design;

FIG. 3 is a bottom plan view of the device shown in FIG. 3;

FIG. 4 is a front elevational view of the device shown in FIG. 2;

FIG. 5 is a right side elevational view of the device shown in FIG. 4;

FIG. 6 is a left side elevational view of the device shown in FIG. 4; and

FIG. 7 is a rear elevational view of the device shown in FIG. 4.

We claim:

The ornamental design for a short-wave therapy apparatus, as shown and described.
